UNITED STATES PATENT OFFICE.

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY.

ELECTRICALLY-LIGHTED SEWING MACHINE.

Application filed August 5, 1924. Serial No. 730,135.

To all whom it may concern:

Be it known that I, DANIEL H. CHASON, a citizen of the United States, residing at Elizabeth, in the county of Union and State of New Jersey, have invented certain new and useful Improvements in Electrically-Lighted Sewing Machines, of which the following is a specification, reference being had therein to the accompanying drawings.

10 This invention relates to electrically lighted sewing machines and has for an object to provide a sewing machine with an efficient lighting device of the type represented in the Patent to Diehl, No. 1,488,233, 15 of March 25, 1924, but which need not be shifted from operative position when the arm side cover-plate is turned to uncover the opening customarily provided adjacent the bend of the sewing machine gooseneck for access to the mechanism within the latter.

Another object of the invention is to provide a simple, neat and inconspicuous mounting for the lighting device of such a 25 nature as to prevent sagging of the lighting device from its normal or horizontal operative position.

Further objects of the invention will appear from the following description and 30 claims.

To the attainment of the ends in view the supporting bracket for the usual lamp-socket, lamp and reflector elements is made 35 separate from the cover-plate and is formed with a small foot-portion which is recessed in the outer wall of the gooseneck beneath the side cover-plate, so that said cover-plate will conceal the foot of said bracket as well as the means by which such foot is secured to the gooseneck. The recess in the gooseneck is preferably in the form of a horizontally disposed slot and one or more of the side edges of the bracket foot are preferably 40 fitted to side wall portions of the slot, thus preventing sagging of the lamp even though a single screw be used to secure the bracket to the sewing machine gooseneck.

In the accompanying drawings, Fig. 1 is 45 a perspective view of an electrically lighted sewing machine embodying the invention. Fig. 2 is a fragmentary vertical section through the side opening adjacent the bend

of the sewing machine gooseneck, looking in a direction toward the free end of the gooseneck. Fig. 3 is a fragmentary horizontal section through the gooseneck and lamp-supporting bracket, and Fig. 4 is a fragmentary disassembled perspective of the gooseneck and lamp-supporting bracket.

In the preferred embodiment of the invention, as illustrated, 1 represents the bed of the sewing machine from which rises the vertical member 2 of the usual gooseneck 3 terminating at its free end in the usual head 4 in which the usual needle-bar 5 and presser-bar 6 are mounted. The gooseneck 3 is formed in its rear side, adjacent its bend, with the usual opening 7, which is normally closed by the removable cover-plate 8 secured in position by the thumb-screw 9. The cover-plate 8 is somewhat larger than the opening 7 and covers the raised rim portion 10 of the rear side wall of the gooseneck adjacent such opening. The rim 10 of the opening 7 is formed with a recess 11, preferably in the form of a horizontal slot having side walls 12, adapted to receive the foot 13 of a bracket to whose body-portion 14 is secured the horizontally disposed lamp-socket 15, carrying 75 the usual lamp-bulb 16 and reflector 17. The foot 13 preferably has its side edges 18 fitted to the side walls 12 of the recess 11 to prevent sagging of the lamp and bracket around the single fastening screw 19.

The bracket 14 is formed with an opening 20 through which passes the nipple 21 having at one end the head 22 and at its opposite end threaded into the lamp-socket 15. A felt bushing 23 and felt washers 24 operate to cushion the lamp and soften the character of the vibration transmitted to the lamp from the sewing machine. Rotary displacement of the lamp-socket is prevented by means of the pin 25 which is fixed 90 to the bracket 14 and enters a notch 26 in the head 22 of the nipple.

By virtue of the present improvement, a substitute cover-plate is not required in equipping a sewing machine with the lighting device. The same cover-plate customarily provided by the sewing machine manufacturer to close the opening in the gooseneck may still be used, and such cover-plate

may be swung to expose the opening in the gooseneck without disturbing the light in any way.

Having thus set forth the nature of the invention, what I claim herein is—

1. The combination with a hollow sewing machine gooseneck having an aperture and a cover-plate removably closing said aperture, of a lighting device including a bracket having a foot-portion recessed in said hollow gooseneck and concealed by said cover-plate.

2. The combination with a hollow sewing machine gooseneck having an opening in its

rear side adjacent its bend and a horizontally extending slot in its outer wall adjacent said opening, of a cover-plate removably closing said opening and covering said slot, and a lighting attachment comprising a bracket having a foot-portion fitted to and secured in said slot and concealed by said cover-plate, said lighting attachment also including a lamp-socket extending horizontally toward the free end of said gooseneck.

In testimony whereof, I have signed my name to this specification.

DANIEL H. CHASON.
